UNITED STATES PATENT OFFICE

170,930

SOUND PRODUCING DEVICE OR SIMILAR ARTICLE

Joseph Long, Belleville, N. J.

Application April 22, 1953, Serial No. 24,617

Term of patent 14 years

(Cl. D56—9)

To all whom it may concern:

Be it known that I, Joseph Long, a citizen of the United States, residing in the town of Belleville, county of Essex, and State of New Jersey, have invented a new, original, and ornamental Design for a Sound Producing Device or Similar Article, of which the following is a specification, reference being had to the accompanying drawing, forming a part hereof:

Figure 1 is a top plan view of a sound producing device or similar article, showing my new design;

Figure 2 is a rear elevational view thereof;
Figure 3 is a front end elevational view thereof;
Figure 4 is a bottom plan view thereof; and
Figure 5 is a side elevational view thereof.

I claim:

The ornamental design for a sound producing device or similar article, as shown.

JOSEPH LONG.
